FIG. 1 is a perspective view, as seen from a top side vantage,
of a portion of a nonwoven fabric showing our new design;
FIG. 2 is a top plan view thereof;

FIG. 3 is a perspective view, as seen from a top side vantage,
of a portion of a nonwoven fabric showing a second embodiment
of our new design; and,

FIG. 4 is a top plan view thereof.

The outer broken line boundaries in FIGS. 1–4, depicting the
boundaries of the claimed design, indicate that a specific
length and width of nonwoven fabric form no part of the
claimed design. The broken lines are for illustrative purposes
only and form no part of the claimed design. The pattern
repeats uniformly throughout the length and width of the
fabric.

The bottom and side edge surfaces of the nonwoven fabric
that are not shown in the drawings or described in the speci-
fication form no part of the claimed design.
